CLAIM

(72) **Inventor:** **Yabin Zhang**, Shenzhen (CN)

The ornamental design for an electronic atomizing device assembly, as shown and described.

(73) **Assignee:** **SHENZHEN SMOORE TECHNOLOGY LIMITED**, Shenzhen (CN)

DESCRIPTION

(**) **Term:** **15 Years**

FIG. 1 is a perspective view of an electronic atomizing device assembly where the first component and second component showing my new design in assembled state of use;

(21) **Appl. No.:** **29/860,984**

FIG. 2 is another perspective view thereof;

(22) **Filed:** **Nov. 24, 2022**

FIG. 3 is a front elevational view thereof;

(30) **Foreign Application Priority Data**

FIG. 4 is a rear elevational view thereof;

Aug. 3, 2022 (CN) 202230504106.0

FIG. 5 is a left side elevational view thereof;

(51) **LOC (14) Cl.** **27-02**

FIG. 6 is a right side elevational view thereof;

(52) **U.S. Cl.**

FIG. 7 is an enlarged top plan view thereof;

USPC **D27/162**

FIG. 8 is an enlarged bottom plan view thereof;

(58) **Field of Classification Search**

FIG. 9 is a perspective view of the electronic atomizing device assembly where the first component removed from the assembly in FIGS. 1-8;

USPC D27/162, 100, 101, 163-170, 172,

FIG. 10 is another perspective view thereof;
